UNITED STATES PATENT OFFICE

WILLIAM E. FRENCH, OF LANCASTER, PENNSYLVANIA, ASSIGNOR TO LANCASTER IRON WORKS, INC., OF LANCASTER, PENNSYLVANIA, A CORPORATION OF PENNSYLVANIA

PORTABLE REPRESS MACHINE

Application filed December 31, 1930. Serial No. 505,808.

The invention forming the subject matter of this application is a portable repress machine particularly adapted for use in repressing of clay shapes such as are commonly used in the building brick and fire brick industries.

In manufacturing fire bricks it is advisable to have the bricks true to size and shape and of uniform density. Fire brick which are true to size and shape completely eliminate irregularities in mortar joints and permits the use of very small mortar joints, thereby increasing the fire resistance of the wall as a whole. Likewise fire brick of this character are more highly refractory due to their ability to more uniformly resist the heat.

Heretofore, it has been the practice to repress these brick in a hand operated portable repress wherein the operator pulled a lever to exert the necessary movement and force to repress these brick. This was a very slow and tiresome job and was later improved upon by a motor being used to perform the repressing operation. However, even with the motor operated repress of the prior art, the operator still has to eject the brick manually from the die after it has been repressed.

The main object of the invention is to provide a machine in which the brick is repressed mechanically after being placed in the die; and in which the repressed brick is mechanically ejected from the die at the termination of the repressing operation.

Another object of the invention is to provide a portable machine in which the motive power for operating the repressing mechanism may be utilized for moving the machine bodily from place to place in the repressing plant.

Other objects of the invention will appear as the following description of a preferred and practical embodiment thereof proceeds.

In the drawings:

Figure 1 is a central vertical section through the portable repress machine constituting the present invention;

Figure 2 is a plan view of the press shown in Figure 1, with the operating motor removed to show details of construction.

Figure 3 is a rear end elevation of the repress machine with parts broken away and

shown in section to illustrate the mechanism for driving the machine as a whole from place to place in the plant;

Figure 4 is a front end elevation of the machine; and

Figure 5 is a fragmentary detail of the repress arms, and illustrating the means in said arms for locking a shaft, forming part of the ejector mechanism, in operative position.

As shown in the drawings, the repress machine comprises a pair of side plates 1 and 2 spaced apart at the rear end thereof by a shaft 3, suitably journaled in said plate and having the wheels 4 and 5 secured to the end thereof in any convenient manner. The front ends of the plates 1 and 2 are connected to each other by a square rod 6, having its opposite ends secured by U-bolts 7 and 8 to angle brackets 9 and 10, bolted to the inside faces of the plates 1 and 2, respectively.

A pivot bearing 11 is mounted on square cross rods 6. A pivot pin 12, forming the lower part of pivot bearing 11, fits in a bored opening in casting 13, which forms the front support for the framework comprising the plates 1 and 2 and the cross square rod 6. The casting 13 may be of any convenient and common mechanical construction and is provided with a forwardly projecting lug 14, having a hole 15 formed therein to receive the bent end 16 of a handle 17 which may be used to guide the machine as a whole in any desired direction.

The motive power for operating the repressing mechanism, and for moving the machine as a whole from place to place, comprises a motor 18 which is suitably bolted to a plate 19 extending from plate 1 to plate 2 and supported thereon by angle brackets 20 and 21, suitably secured to the plates 1 and 2. The bolts 22 and 23 are used for securing the motor 18 to the plate 19.

The shaft 24 of the motor 18 is operably connected by a link belt and pulley mechanism, designated generally by the reference character 25, to the shaft 26 of a reducer 27, the base of which is bolted or otherwise suitably secured to a cross plate 28 extending between the side plates 1 and 2 and suitably

secured to angle brackets 29 and 30, which are bolted in turn to the said side plates 1 and 2.

The reducer shaft 31 extends across the machine between the side plates 1 and 2, and has a sprocket gear 32 fixed to one end thereof and meshing with a sprocket chain 33, extending a sprocket gear 34 which is mounted to rotate freely on the shaft 3, as shown clearly in Figure 3. A driving collar 35 is keyed on the shaft 3 to rotate therein and is provided with a series of holes 36 adapted to register with similar holes 37 formed in the sprocket gear 34. These holes 36 and 37 are adapted when registered, to receive a driving pin 38 for the purpose of imparting the rotation of the sprocket gear 34 to the shaft 3 and thereby to the wheels 4 and 5 for the purpose of propelling the repressing machine as a whole from place to place, whenever found necessary or desirable.

The other end of the reducer shaft 31 has a sprocket gear 38' fixed thereto; and a sprocket chain 39 extends around the gear 38 and around the second sprocket wheel 40 which is suitably secured to a crank shaft 41 suitably journaled in bearings formed in the opposite supporting plates 1 and 2. Upon the crank throw 42 of the crank shaft 41 there is mounted a connecting rod 43 which is pivoted at its outer end by means of a pivot bolt 44 to one end of a fulcrum arm 45, the other end of which is supported, pivot fashion, on the top of an adjusting screw 46.

Two of these adjusting screws 46 are shown in Figure 4 of the drawings as being adjustably mounted on angle brackets 47 and 48 having the lower flanges thereof connected by a bracing plate 49. The center part of the fulcrum arm 45 has upturned lugs 50 formed thereon to receive and seat a shaft 51 for supporting a roller 52, the ends of the up-turned lugs 50 being suitably slotted to form journal bearings for the said shaft 51.

The roller 52 is adapted to contact with a wear plate 53 secured by a shear pin 54 to the bottom end of a plunger 55 which is slidably mounted in the cross rails 56 and 57 extending between and suitably secured to the side plates 1 and 2 of the machine framework. The top plate 58 of the plunger 55 extends substantially across the machine between two angle iron brackets 59 and 60 (see Figure 2) which form the support for the die 61 in which the bricks are to be repressed.

The fulcrum arm 45 carries a shaft 62 which extends in opposite directions through the side plates 1 and 2 of the framework. The projecting end of the shaft 62 has the arms 63 and 64 pivotally mounted thereon; and these arms extend upwardly from the shaft 62 to form a yoke adapted to swing about the shaft 62 as an axis toward and

away from the die 61. To form this yoke the upper ends of the arms 63 and 64 are screw-threaded to receive suitable adjusting and lock nuts for securing a cross plate 65 to the upper ends of said arms; the said plate 65 being suitably apertured to form a handle 66.

The shaft 62 which carries the arms 63 and 64 at its opposite ends is mounted to slide snugly in arcuate slots formed in the opposite supporting plates 1 and 2, only one of these slots 67 being shown in Figure 1 of the drawings. These slots are struck from a center formed by the contact line of the fulcrum arm 45 with the top of the adjusting screws 46 in order to maintain the axis of the shaft 62 in alignment with the axis of the plunger 55.

The slots 67 permit the fulcrum arm 45 and its associated parts to be removed without dismantling the entire machine. The cross bars 88, see Figure 1, are provided to act as a stop for fulcrum arm 45 at the time that ejecting motion takes place. At all other times the fulcrum arm 45 is clear of these bars.

The plunger 55 is provided centrally with a slot 68 adapted to receive slidably the end 69 of an ejector arm 70, which is pivotally mounted intermediate its ends on the ejector shaft 71. The ends of the shaft 71 are slidably mounted in slots formed in the opposite side plates 1 and 2, of which slots only the one formed on the side plate 1 and designated by the reference character 72 is illustrated in the drawings. The projecting ends of the shaft 71 extend into the path of movement of the arms 63 and 64, and are adapted to seat in arcuate slots (shown clearly in Figure 5) formed in the rear edges of the arms 63 and 64. One of these arcuate slots 73 is shown in Figure 5 as being formed on the arm 64, with a part of the shaft 71 seated therein. An adjustable link 74 has one of its ends pivotally connected to the rear end of the ejector arm 70, and has its other end pivotally connected to the fulcrum arm 45 between the ends thereof, and in the slot formed in said arm 45 for this purpose.

The side plates 1 and 2 are provided with stop plates 75 and 76 suitably secured to said side plates and arranged to limit the forward movement of the arms 63 and 64 to a position in which the cross plate 65 is directly above the plunger 55, that is in the position required for repressing a brick previously placed in the die 61. The projecting ends 77 and 78 of the shaft 71 serve as stops to seat in the slot 73 and limit the movement rearwardly of the said arms 63 and 64.

In order to relieve the projecting end 77 and 78 of the shaft 71 from receiving the full strain of stopping the rearwardly movement of arms 63 and 64, bumpers 89 in the form of angle brackets with fabric facing

(brake lining) are bolted to side plates 1 and 2.

The framework of the machine is provided with suitable switches 79 and 80 adapted to be set in operation by contact with one of the arms 63 or 64 in its limit position in order to set in motion the motor 18 and thereby start the mechanism in operation either for repressing or for ejecting a brick placed in the die 61. The motor is provided with suitable limit switches and braking mechanism which causes the motor to stop in a predetermined position, which is the position on dead center of the connecting rod 43 as shown in Figure 1 of the drawings. This switch and brake mechanism are not shown or described in this application, because they are old and well known in the art and their details of construction form no particular part of the present invention.

The motor mechanism is designed so that upon actuation of either of the switches 79 or 80, the motor will rotate to move the rod 43 and the mechanism connected therewith through a single cycle of movement from the position shown in Figure 1 of the drawings to exactly the same position at the end of that cycle of movement. At the completion of a cycle of movement the motor stops and remains stopped unless and until the arms 63 and 64 are moved from contact position with one of the switches 79 or 80 into contact position with the other of said switches. It is to be understood however, that the machine may be provided with a switch for operating the motor independently of either of the switches 79 or 80, as for example, where it may be found necessary to repeat a repressing operation on the same brick in the die 61 or to repeat an ejecting operation from the said die 61. In all cases however, it must be understood that when the motor is once started it will not stop until it has completed a single cycle of operation so that the connecting rod 43 and associated mechanism comes to rest in the position shown in Figure 1 of the drawings.

In order to regulate the pressure of the plunger 58 in the pressure mold, the bearings for the shaft 62 are constructed to apply a yielding pressure to said plunger. As shown in the drawings, each bearing for the shaft 62 includes a laterally extended end 81 formed on the lower end of the yoke arms 63 or 64 and shaped to provide the upper half of the bearing for shaft 62. The lower half of said bearing comprises a block 82 adapted to be secured to the end 81 by bolts 83 passing through suitable registering apertures in the end 81 and block 82.

The bolts 83 extend through suitable apertures in a rubber block 84 and in a clamping plate 85; and pressure adjusting and lock nuts 86 and 87 are threaded on to the screw threaded end of each bolt 83 to adjust the

pressure desired on plunger 58 through blocks 84 and to clamp the shaft 62 yielding against the upper half of its bearing in the end 81 of the yoke arms 63 and 64.

These rubber bearing inserts provide a light weight positive means for regulating the limit of pressure of the plunger 58 on the bricks being repressed in the mold 61. They also permit much higher pressures to be secured than can be obtained by the use of such springs as are capable of being employed in the limited space at the end bearings of the yoke arms.

In the operation of the invention: Let it be assumed that the repressing machine is in the position shown in Figure 1 of the drawings and that a brick has been placed in the die 61 for repressing purposes. Although one of the repressing yoke arms 63 or 64 is in contact with the switch 79, the motor 18 is at rest. When the repressing yoke is pulled over to repressing position by the handle 66, one of its arms will contact with the switch 80 and set the motor 18 in operation. This sets the crank shaft 41 in rotation and swings the fulcrum arm 45 about its pivotal connection on top of the adjusting screws 46, thereby moving the shaft 62 downwardly in the slots 87. At the same time the roller 52 impinges upon the wear plate 53 of the plunger 55 and forces the plunger with its head 58 against the movable bottom of the die 61 to repress the brick placed therein.

It will be apparent of course, that while the repressing yoke is in repressing position the ejecting shaft 71 will be free to move in the slots 72 so that the ejector arm 70, or rather the end 69 thereof, merely slides to and fro in the slot 68 formed in the plunger 55. Continued rotation of the crank shaft 41 eventually brings the connecting rod 43 and its associated mechanism to the predetermined stop position shown in Figure 1 of the drawings, and completes the repressing operation on a brick placed in the die 61.

The repressed brick is now ready for ejection from the die 61. Heretofore, this ejecting movement has been performed manually. In the present case the ejection is performed merely by moving the repressing yoke from its vertical repressing position to the inclined ejecting position shown in Figure 1 of the drawings. In moving this yoke from the vertical to the inclined position the curved guiding edge 81 of the slot 73 contacts with the projecting ends 77 and 78 of the shaft 71 and locks this shaft against sliding movement in the slot 72, at the same time the switch 79 is set in operation to cause rotation of the motor 18. The connecting rod 43 and the associated mechanism move exactly as they did in the repressing operation. However, since the shaft 71 is now locked in position the ejecting arm 70 is rocked about the shaft 71 and the end 69 is rocked about the shaft 71 and the end 69.

thereof engages a rounded lug 82 in the upper end of the slot 68 to raise the plunger head 58 sufficiently to eject the brick from the die 61. During this ejecting operation, the plunger 55 is raised clear of the roller 52 and is supported wholly by the end 69 of the ejecting arm 70.

Whenever it is found necessary or desirable to move the repressing machine from one place to another, the pin 38 may be inserted in a pair of registering apertures 36 and 37 of the driving collar 35 and sprocket gear 34, respectively, in order to cause rotation of the driving and supporting wheels 4 and 5 to effect movement of the machine as a whole, which may be guided by suitable operation of the caster 13 under control of the handle 17.

While I have shown and described a particular embodiment of my invention, it must be understood that the invention is not to be considered as limited to the particular form shown, but extends to all construction for performing the same function and as limited only by the claims appended hereto.

What I claim is:

1. A press comprising an open ended mold chamber adapted to receive material to be pressed, means for exerting pressure on material in said chamber and including a closure for one end of said chamber and mechanism automatically started in operation by the closing of said chamber to drive said pressure means, said mechanism being normally inoperative.

2. A press comprising an open ended mold chamber adapted to receive material to be pressed, means for exerting pressure on material in said chamber and including a closure movable to a predetermined position to close one end of said chamber and to a predetermined chamber opening position, mechanism automatically set in operation by movement of said closure to chamber closing position to operate said pressure means, and means set in operation by said mechanism on movement of said closure to said predetermined chamber opening position for ejecting material from said chamber, said mechanism being normally inoperative until set in operation by movement of the closure from one predetermined position to the other.

3. A press comprising a mold chamber adapted to receive material to be pressed, means for opening and closing said chamber, pressure means for exerting pressure on material in said chamber and including an actuating lever, a driven shaft, and means for actuating said lever from said driven shaft, said driven shaft and means being automatically stopped when the said lever reaches a predetermined position after an actuation thereof.

4. A press comprising a mold chamber adapted to receive material to be pressed, means for opening and closing said chamber,

means for exerting pressure on material in said chamber and for ejecting material from said chamber, and means for automatically operating said pressure means by movements of the first named means to press and eject material from said chamber successively.

5. A press comprising a mold chamber adapted to receive material to be pressed, pressure means adapted to press the material in said chamber, operating mechanism for said pressure means, and a movable closure for said chamber, said operating mechanism being automatically started in operation by positioning the closure in chamber closing position and stopped after a pressure operation.

6. A press comprising a mold chamber adapted to receive material to be pressed, pressure means adapted to press the material in said chamber, operating mechanism for said pressure means, a movable closure for said chamber, and means automatically operated by moving the closure to chamber closing position for operating said mechanism through a predetermined cycle of movement and to stop the operation thereof at the end of said cycle.

7. A press comprising a mold chamber, a movable closure forming one wall of said chamber, a plunger forming another wall of said chamber, an actuating lever connected to move said closure and plunger toward and from each other, a driven shaft, and means for automatically starting said shaft to actuate said lever by said shaft and from a predetermined position at the start of an actuating movement to the same predetermined position at the end of such movement and to stop said shaft automatically at the end of such movement.

8. A press comprising a mold chamber, a movable closure forming one wall of said chamber, a plunger forming the opposite wall of said chamber, an actuating lever connected to move said closure and plunger toward and from each other, ejecting mechanism pivotally connected to said actuating lever, a driven shaft, and means connected to said shaft for automatically actuating said lever and ejecting mechanism.

9. A press comprising an open ended mold chamber, a plunger slidable in and forming the bottom wall of said chamber, an actuating lever having a pair of laterally extending trunnions and engaging and actuating said plunger, ejecting mechanism pivotally connected to said lever and engaging said plunger, a yoke straddling said chamber and having its arms journaled yieldingly on said trunnion, a closure carried by said yoke and forming the top wall of said chamber when positioned thereon, and means automatically operable for actuating said lever to move said plunger a predetermined distance in said chamber when the closure is in chamber

closing position and for actuating said lever and ejecting mechanism for moving said plunger a further predetermined distance in said chamber when the said closure yoke and closure are moved to a predetermined position away from closing position.

10. A press comprising an open ended mold chamber, a plunger slidable in said chamber and forming the bottom wall thereof, an actuating lever having a pair of trunnions extending laterally therefrom and engaging and actuating said plunger, ejecting mechanism pivotally connected to said lever and also engaging said plunger, a yoke straddling said chamber and having its arms journaled yieldingly on said trunnion, a closure carried by said yoke and movable by said yoke to form the top wall of said chamber, and means automatically operable by moving the yoke to chamber closing position for moving said plunger a predetermined distance into said chamber and operable by moving said yoke to a predetermined position away from chamber closing position for operating said ejecting mechanism to move said plunger a further predetermined distance into said chamber.

11. A press comprising a mold chamber, a plunger forming the bottom wall of said chamber, a lever having a pair of laterally extending trunnions and engaging said plunger to actuate the plunger, a closure yoke straddling said chamber, the lower end of each arm of said yoke being shaped to form a bearing for one of said trunnions, complementary bearing blocks for said trunnion, a clamping plate, a block of yielding material arranged between said clamping plate and one of said complementary bearing blocks, and means for holding said complementary bearing blocks and yielding material and clamping plate in assembled position on each of said arms.

12. A press comprising an open ended mold chamber, a plunger forming the bottom wall of said chamber, an actuating lever having a pair of laterally extending trunnions and engaging said plunger to actuate it, a closure yoke straddling said chamber and having split bearings at the lower end of each of its arms to form journals for said trunnions, and means including blocks of yielding material for clamping said bearings yieldingly to said trunnion, a closure carried by said yoke and forming the top wall of said mold when positioned thereover, and means for actuating said lever.

13. A press comprising an open ended mold chamber, a plunger forming the bottom wall of said chamber, a closure yoke straddling said chamber and having a plate secured thereto to form the top wall of said chamber, actuating mechanism for said plunger, a motor, and means operated by positioning said yoke with its plate in a pre-

determined position above said chamber to start said motor and move said actuating mechanism from a predetermined position and to stop said motor when said mechanism arrives at the same predetermined position.

14. A press comprising framework including a pair of parallel spaced apart plates, a mold chamber supported by said plates, a plunger slidable between said plates to form the bottom wall of said chamber, a yoke straddling said plates and having a closure adapted to form the top wall of said chamber, an actuating lever for said plunger having laterally extending trunnions slidable in slots formed in said pair of plates, yieldable bearings secured to the end of the arms of said yoke and clamped to said trunnion outside of said plates, an ejecting lever having one end thereof engaging said plunger and having trunnions intermediate the ends thereof slidably mounted in slots formed in said plates, the arms of said yoke being provided with notches adapted when the yoke is in open position to engage the last named trunnion to lock said ejecting lever rotatably about a fixed axis on said parallel plates and means for actuating said actuating lever to operate said plunger directly by said actuating lever when the said closure is in closing position on said chamber and to actuate said ejecting lever when seated in the notches on the arms of said yoke.

In testimony whereof I affix my signature.
WILLIAM E. FRENCH.
